A CORPORATION.

VAPOR-LAMP.

No. 826,297.

Specification of Letters Patent.

Patented July 17, 1906.

Application filed October 20, 1905. Serial No. 283,694.

To all whom it may concern:

Be it known that I, ALONZO A. WARNER, a citizen of the United States, residing at New Britain, in the county of Hartford and State 5 of Connecticut, have invented certain new and useful Improvements in Vapor-Lamps, of which the following is a specification.

My invention relates to improvements in vapor-lamps; and the objects of my improvement are simplicity and economy in construction and convenience and efficiency in use.

In the accompanying drawings, Figure 1 is a central vertical section of my lamp on a line transversely to the axis of the pinion 15 which operates the shutter. Fig. 2 is a detached side elevation of the burner or wick-tube.

A designates the font, having a fixed guide-tube 3 in the center of its top, inside of which 20 guide-tube the shutter 4 is fitted to move up and down as the pinion 5 and its shaft 6 are rotated. A row of perforations 7 in the side of the shutter serve as a rack for the said pinion to engage. In the bottom of the font A 25 two or more elevations 8 are formed, upon which to mount the fixed nut 9, so that the fluid within the lamp-font can enter the inner side of the nut by flowing in between the elevations 8. The lower end of the wick-tube 10 30 is provided with a rolled thread 11, the exterior of which fits the nut 9, so that the removable wick-tube can be inserted and held in place by screwing the lower end into the nut and removed by unscrewing the said 35 threaded end from the nut. A removable wick-tube that screws into a nut in the bottom of the font is old; but in the present case the thread is rolled in the metal so as to form a thread both on the outside and inside of the 40 wick-tube. This thread is carried up on the wick-tube a little higher than the main part of the top of the font and is therefore extended to a point above the intended fluid-level of the font. The tube is filled with a sub- 45 stantially round wick 12, preferably of asbestos, the size and hardness of the wick being such that it rests on the innermost projections of the female thread inside of the wick-tube and leaves the groove of the thread open, 50 as shown, whereby the fluid in the font may flow upwardly in this thread or spiral passage and keep the wick wet up to the level of the fluid in the font, whereby the lamp is more effective than it would be if it had to draw

the fluid up from a lower level. This is especially the case with an asbestos wick, which is not quite so absorbent as a cotton or other ordinary wick.

The body of the wick-tube is of a smaller diameter than the shutter; but its upper end is provided with two beads or enlargements 13 and 14, the diameter of the wick-tube at the most prominent part of these beads being approximately the same as that of the inner diameter of the shutter 4. In the beads I 65 form the jet-perforations 15, preferably a little above their summit. The upper end of the wick-tube is closed by a cap 16. A perforated ring 17 is placed on the wick-tube just under the lower bead 14, the exterior 70 diameter of the ring being substantially the same as that of the bead, so that the shutter can pass it, thereby making an annular chamber which is filled with a suitable priming-wick 18, preferably of asbestos. The ring 17 75 may be secured in place in any ordinary manner. As shown, it is secured by making a slight swell 19 in the wick-tube just below the ring. I prefer to have the wick 12 at its upper end stop short of the lower bead 14, so 80 as to leave an unobstructed gas-chamber 20, Fig. 1, in the upper end of the wick-tube, and thereby more nearly equalize the pressure of the gas that issues from all of the jets.

For starting the lamp the shutter may be 85 turned up to its full height and the lamp shaken a little to throw some of the alcohol up inside of the shutter and saturate the priming-wick 18. The shutter may then be turned down to the position shown in Fig. 1, 90 or a little lower, so as to expose the perforations in the ring 17 and the inclosed priming-wick, which may be lighted with a match. In a short time the lamp will be hot enough 95 to generate gas, which will come out at the jets and be ignited. The shutter may then be turned up far enough to extinguish the flame at the ring 17, while it still issues from both rows of jets. The flame at the lower row of jets may be extinguished at any time 100 desired by raising the shutter so as to close that row, and raising the shutter to its full height will extinguish the flame at both rows of jets.

By having the upper end of the wick below 105 the jets there is no consumption of the wick by burning. The priming or starting wick if of asbestos, will be practically indestructible,

and it is applied at a small cost with none of the disadvantages of an outer wick that extends substantially the length of the wick-tube.

5 I claim as my invention—

1. In a vapor-lamp, the combination of a lamp-font with a fixed nut on the inside at the bottom of the said font, the interior of the said nut communicating through its lower end with the said font, a removable wick-tube having a rolled thread at its lower end whereby the said lower end is both exteriorly and interiorly threaded, and a wick within the said tube bearing on the inward projections of the inner thread at the lower end of the said tube, leaving a spiral passage around the wick inside the lower end of the said tube
- 10
- 15

for the fluid in the font to pass upwardly through from the lower end of the said nut to the fluid-level of the font.

2. In a vapor-lamp, the combination of a wick-tube having jet-perforations at its upper end with a perforated ring mounted on the said tube below the said jet-perforations for forming an annular wick-chamber inside 20 of the said ring and outside of the said wick-tube, a priming-wick within the said chamber, and a shutter surrounding the wick-tube and adapted to close over the said ring and jets.

ALONZO A. WARNER.
